[57] **ABSTRACT**

An omnidirectional magnetic particle flaw detecting apparatus is disclosed. The apparatus includes two sets of magnetizing coils crossed in such a manner that an elliptical rotating magnetic field may be formed with its major axis running along the width direction of test material at the center of the crossed coils at the time when said coils are air-cored, and a circular rotating magnetic field may be formed on the surface part of the test material at the time when such material is inserted into the coils as the material progresses in the lengthwise direction.

FIG. 12

OMNIDIRECTIONAL MAGNETIC PARTICLE FLAW DETECTING APPARATUS

BACKGROUND OF THE INVENTION

1. Field of the Invention

The present invention relates to a magnetic particle testing apparatus for flaw detection of magnetized articles and, more particularly, to an omnidirectional magnetic particle flaw detecting apparatus which is able to detect flaws regardless of their direction relative to the device so that flaws in a test material lying in a direction perpendicular to the direction of travel of the test material can be detected with the same level of detecting sensitivity as flaws lying along the direction of travel of test material.

2. Description of the Prior Art

In the case of flaw detection of magnetized steel or the like, it is difficult to detect flaws lying along the direction of travel (lengthwise) of the material under scrutiny while detecting flaws lying in the direction perpendicular to the direction of travel since the magnetizing direction must be perpendicular to the direction along which flaws lie. In such case, therefore, different magnetizing units for flaw detecting are used in the lengthwise and widthwise directions of test material. Thus, according to the conventional methods for magnetic particle flaw detection, at least two different units are required, making operations complicated and its automation very difficult in view of the necessity of taking into consideration the relationships between magnetizing units and between the test material and each respective unit.

As one of the improvements made to the conventional magnetic particle flaw detecting apparatus in order to solve the above-mentioned problem, so-called crossed coils, which cross each other at right angles, are used as magnetizing coils. This system utilizes current with phases different by 120° in a three-phase current source. However, this system, to say nothing of the conventional apparatus, has not been successful in solving the problem of detecting flaws lying in various directions, all in the same level of detecting sensitivity.

SUMMARY OF THE INVENTION

It is an object of the present invention to provide a magnetic particle flaw detecting apparatus, which is very handy, and which can detect flaws lying in various directions, all in nearly the same level of detecting sensitivity.

Another object of the present invention is to provide a magnetic particle flaw detecting apparatus which can detect flaws at any position on the surface away from the intersection of coils: that is, which can perform omnidirectional detection.

A further object of the present invention is to provide a magnetic particle flaw detecting apparatus which is so efficient that it can detect flaws at the same time all over the entire width of wide, plain materials, such as slab or thick plate, in all directions, without contacting flaws.

These and further objects of the present invention will appear more fully from the following detailed description and embodiments.

In order to detect flaws lying in various directions, all in the same level of detecting sensitivity, it is necessary to make the magnetic field produced on the surface of the test material equal in all directions. That is, a circu-

lar rotating magnetic field should be formed on the surface of the test materials. However, in case magnetizing coils, which are to form a circular rotating magnetic field when no test material is positioned therein, are used for flaw detection of materials having a length greater than the width, and particularly in case such materials are inserted into the coils along their lengthwise direction, the magnetic field produced on the test material in the lengthwise direction extends to a much greater extent than that in the widthwise direction, as the material itself has been magnetized. This results in the reduction of the magnetic field produced in the widthwise direction relative to the lengthwise direction, making it impossible to conduct tests with constant detecting sensitivity in every direction over the test material.

As a result of efforts made by the inventors of the present invention, it was found that omnidirectional constant sensitivity flaw detection is made possible by using, as magnetizing coils, two coils having a certain coil turn ratio range, the coils crossing each other and forming an acute angle relative to the direction of travel and connected with a three-phase current source. Magnetic particles are sprayed onto the test material during magnetization, as well known in the prior art.

30 BRIEF DESCRIPTION OF THE DRAWINGS

FIG. 1 is a perspective view of magnetizing coils of the flaw detecting apparatus according to the present invention.

35 FIG. 2 shows a circuit for the connection of the electric source with the coils of FIG. 1.

FIG. 3 shows the relationship between coil turn ratio and the major axis-minor axis ratio of the elliptical rotating magnetic field formed at the center of the coils, when these coils are air-cored.

40 FIG. 4 shows the relationship between the angles formed by crossing magnetizing coils and the major axis-minor axis ratios of the elliptical rotating magnetic field formed at the center of the coils, when these coils are air-cored.

FIG. 5 shows the result of flaw detection achieved by the flaw detecting apparatus of the present invention.

45 FIG. 6 shows the slit flaws in billets used for the test of FIG. 5.

FIG. 7 is a front view of a billet as it is inserted into a magnetizing coil.

50 FIG. 8 shows the result of flaw detection carried out by a prior art flaw detecting apparatus.

FIG. 9 is a perspective view of the apparatus of the present invention having two sets of crossing magnetizing coils.

55 FIG. 10 is a schematic illustration of a device for switching the electric source between coils for use in the apparatus of FIG. 9.

FIG. 11 is a perspective view of magnetizing coils used in the embodiments of the present invention.

60 FIG. 12 is a perspective view of a magnetizing composite coil made of the magnetizing coils of FIG. 11.

FIG. 13 shows an electric power circuit connected with the magnetizing composite coil of FIG. 12.

DESCRIPTION OF THE PREFERRED EMBODIMENTS

As shown in FIG. 1, a magnetizing coil 1 is constructed with a first composite coil 2 and a second composite coil 3.

The first composite coil 2 has a rectangular shape, and has an outer coil 4 and an inner coil 5. The outer coil 4 and inner coil 5 are wound on the same reel, but have different numbers of turns.

The second composite coil 3 is constructed in the same manner as the first composite coil 2. The two composite coils 2 and 3 are arranged to cross each other at the centers respectively of their corresponding horizontal parts, thus forming the magnetizing coil 1.

FIG. 2 shows the connection between the electric sources respectively for the first composite coil 2 and the second composite coil 3.

In FIGS. 1 and 2, numerals 8 and 9 denote terminals of the outer coil 4 of the first composite coil 2 for the connection of an electric source; numerals 10 and 11 denote terminals of the inner coil 5 for the connection of the electric source; numerals 12 and 13 denote terminals of the outer coil 6 of the second coil composite 3 for the connection of the electric source; and numerals 14 and 15 denote terminals of the inner coil 7 for the connection of the electric source. Letters *u*, *v*, and *w* of three-phase current source 17 denote phases for the output terminals on the secondary side of the transformer which is subjected to V wire connection in the three-phase electric source.

Alternating current is supplied to the outer coil 4 of the first composite coil 2 from the terminals 8 and 9, connected with the alternating current source 17; and an alternating current with a certain phase difference, in this case 120° from the phase of the current supplied to said outer coil 4, is supplied to the inner coil 5 in the reverse direction to that to the outer coil 4. The same description applies to alternating current supplied to the second composite coil 3.

The coil turn ratio between the outer and the inner coils of respective composite coils is determined by considering the shape of the test material, the phase difference between alternating current supplied to the coils and other factors, so that a nearly circular rotating magnetic field may be formed on the surface of the test material during the flaw detecting process.

The crossing angle θ between the composite coils 2 and 3, defined in the region through which the test materials travel, is so determined that a circular rotating magnetic field may be formed on the surface of the test material.

The shape of the composite coils is not limited to a rectangle, but may vary appropriately according to the sectional form of test materials, and in each composite coil the two coils may be placed side by side instead of the above-mentioned superposition of one coil over the other.

The following is a detailed explanation of the magnetic particle flaw detecting apparatus according to the present invention. As shown in FIG. 2, alternating current having a phase difference of 120° relative to each other, is supplied to the coils 4 and 5 of the first composite coil 2. The same thing applies to the coils 6 and 7 of the second composite coil 3. Also, as shown in FIG. 2, the relation between the first composite coil 2

and the second composite coil 3 is maintained through their connection with the electric sources.

The coil turn ratio between the outer coil 4 and the inner coil 5 of the first composite coil 2 is preferably between 1.5 and 2.5. The same ratio also applies to the second composite coil 3. Outer coils 4 and 6 and inner coils 5 and 7 have, respectively, the same number of turns.

If the coil turn ratio is less than 1.5, the major axis-minor axis ratio of an elliptical rotating magnetic field will greatly increase, but this is not practical, since this requires a large amount of power to attain the required detecting sensitivity. On the other hand, if the coil turn ratio is more than 2.5, the major axis-minor axis ratio will approach $\sqrt{3}$, which situation will appear as if the major axis and the minor axis of the elliptical rotating magnetic field were reversed in comparison with the air-cored arrangement when the material is in the flaw detecting test, thereby causing a difference in detecting sensitivity between tests in the width and in the length of the test material, which does not meet the purpose of the present invention.

FIG. 3 shows the relationship between the above-mentioned coil turn ratio and the ratio between the major axis and the minor axis of the elliptical rotating magnetic field at the center when the coils are air-cored; if the coil turn ratio is less than 1.5, the major axis-minor axis ratio will gradually approach infinity as the ratio approaches 1; and as the coil turn ratio becomes greater, the major axis-minor axis ratio gradually approaches $\sqrt{3}$.

As mentioned above, the desired rotating magnetic field can be obtained by determining the appropriate coil turn ratio according to the present invention. Further, for readily adjusting the ratio between the major axis and the minor axis of the elliptical rotating magnetic field to the desired value, the composite coils having the above-mentioned coil turn ratio, are made to cross each other, but it is then necessary to make the crossing angle θ acute. In case this angle θ is an obtuse angle, that is, more than 90°, it will be impossible to obtain an elliptical rotating magnetic field having its major axis running along the width of the test material when the coils are air-cored.

According to the knowledge and experience of the inventors of the present invention, an angle θ of less than 60° is effective to obtain an optimum elliptical rotating magnetic field; if the angle θ is too small, the effective width of the passage of material will be narrowed, making it necessary to increase the size of the magnetizing coils. FIG. 4 shows the relationship between the crossing angle of coils on one hand and the ratio between the major axis and the minor axis of the elliptical rotating magnetic field at the center of the coils on the other hand. It is apparent that the optimum major axis-minor axis ratio can be obtained from a crossing angle between 60° and 30°. Detection signals generated by the magnetic flaw detecting apparatus of the present invention are processed in a known circuit and are output as flaw detecting signals.

In connection with the above explanation of the construction of the apparatus of the present invention, the following is an example of flaw detection, using the apparatus of the present invention.

Magnetic flaw detection (the determination of leakage flux) was conducted with a flaw detecting apparatus constructed with magnetic coils, each having a coil

turn ratio of 4 : 2 obtained by making the number of actual turns of the outer coil and of the inner coil, respectively, 4 and 2. The composite coils are then crossed, as shown in FIG. 1, to form a crossing angle θ of 60° and are connected to the current course as shown in FIG. 2. A square steel billet having one of its sides extending 80 mm, made with slits (flaws) therein as shown in FIG. 6 and positioned as shown in FIG. 7, is tested by the subject device, the composite coils of which receive a 900 amp. current. Magnetic particles were sprayed over the surface of the square billet from four magnetic particle sprayers 19, one being directed against each side of the billet, as is well known in the art. The results of the measurement of leakage flux, for quantitative confirmation of the efficacy of the subject invention, are shown in FIG. 5. As is obvious therefrom, all the slits *a*, *b*, and *c* were detected as flaws with nearly the same detecting sensitivity even though slit *a* was perpendicular to the direction of travel A of the billet of rolling billets; slit *b* was at 45° to this direction and slit *c* was parallel with said direction. This clearly establishes that all slits can be detected with nearly the same detecting sensitivity.

FIG. 8 shows the result of a flaw detection test which was made on a material of the same kind and size as mentioned above, that is, a square steel billet, with a prior art apparatus constructed with two coils, each coil having six turns and crossed at right angles. As seen in the figure, the apparatus does not overcome the prior art difficulties specified in the instant application and achieves poor results compared with the test obtained with the subject invention. More particularly, the level of detecting sensitivity for a slit lying perpendicular to and parallel with the direction of progress is reversed between FIG. 8 and FIG. 5 so far as the detecting position is in the vicinity of the center of the intersection of the magnetizing coils. This proves that the apparatus of the present invention is efficient; it works with nearly the same level of detecting sensitivity regardless of the directions of slits (flaws) made on the material.

As mentioned above, the omnidirectional magnetic particle flaw detecting apparatus according to the present invention can work with the same level of detecting sensitivity regardless of the direction of flaws. However, flaws far away from the intersection of the magnetizing coils may not be efficiently detected, that is, the apparatus may work with low detecting sensitivity.

FIG. 9 is a perspective view of a magnetic particle flaw detecting apparatus designed to obviate this disadvantage. Magnetizing coil 21 consists of composite coils 23 and 24, constructed as detailed above, and is superposed with similarly constructed magnetizing coil 22 consisting of composite coils 26 and 27. The device may be coupled to a power source in a manner similar to that detailed above. The coils are positioned such that an imaginary line connecting the points of intersection 25 of the composite coils 23, 24 and an imaginary line connecting the points of intersection 28 of the composite coils 26, 27 cross each other at right angles and at the respective center of the imaginary lines.

If the angle of intersection formed by the imaginary lines deviates from 90°, the rotating magnetic field is deformed, making uniformly effective detection impossible. As for materials having such sectional form as of shaped steel, the angle should be changed according to the section form.

The apparatus of the present invention is constructed as mentioned above, and shall be operated as follows:

A test material, such as a square steel billet, is introduced into the structure built as shown in FIG. 9 in the direction of the arrow A. However, current should not be supplied simultaneously to the magnetizing coils 21 and 22; this introduction would create a mixture of rotating magnetic fields formed by the respective coils 21 and 22 which effects the range of the flaw detection. In order to avoid this complication, the apparatus of the present invention is so operated that the current supply is alternated at a high rate between the coils 21 and 22, so that they alternately and singly operate for a limited time. This method of current supply will not cause mixing of the elliptical rotating magnetic fields produced by respective coils, making it possible to carry out flaw detection on a multi-face basis.

FIG. 10 shows an embodiment of a device for switching the power source for the above-mentioned purpose. This device is so constructed that a thyristor 32 and a step-down transformer 33 are connected in series, thereby alternating the current from the source between the coils 21 and 22. If the rate of travel of the test materials is assumed to be 60 m/min. (1 m/sec.) and an alternating current of 60 Hz is switched every 2 cycles (1/30 sec.), the material will progress 6.7 cm during one alternation cycle.

If the magnetizing range in the direction of travel of the coil is designed to be about 60 cm, it will be covered by about 10 alternations of magnetizing, which will ensure sufficient application of magnetic particles to flaws. While current is introduced to the other magnetizing coil, magnetic particles are maintained by means of their own inertia.

It is unnecessary to alternatively completely cut off the current supply but it is possible, according to the present invention, to supply a small amount of current, say, less than 10 percent of the normal supply, since no substantial rotating magnetic field is formed thereby. Thus, flaw detection of square billets over the entire surface area can be made in one pass through the apparatus of the present invention with constancy in every direction and with a high level of detecting sensitivity.

The operation of the magnetic particle flaw detecting apparatus for testing broad articles like plate, is explained, as follows: In this case, the composite coils made of two sets of magnetizing coils are not sufficient to cover the breadth of such material. Therefore, a magnetizing coil series made of more than two sets of magnetizing coils connected in series at the intersections thereof are used.

However, in such a case, magnetic fields interfere with each other at the conjunction of the intersections of coils in a series, so that the magnetic fields in the widthwise direction are cancelled, leaving those of lessened level of sensitivity only in the direction of travel.

The crossed coils shown in FIG. 12 may be used to solve the above-mentioned problem.

FIG. 11 shows a magnetizing element coil 41, which is made by crossing two coils 42 and 43 and forming a certain crossing angle θ between their respective top parts 44 and 47 and also between their respective bottom parts 45 and 48. Numerals 46 and 49 indicate sides, respectively, of the coils 42 and 43. The crossing angle θ and the current phase difference between the coils 42 and 43 are left to choice in view of the above disclosure. Tabs 73, 74, 75 and 76 indicate terminals

for connecting the coils with an electric power source.

According to the present invention, more than two of such unit magnetizing element coils, as shown in FIG. 12, may be connected in series into two conjunctive magnetizing coil series. Two such series 51 and 52 may be superposed so that the intersection 56 of the magnetizing element coils of the second conjunctive magnetizing coil series 52 is placed at the center of the opening 55 between the connecting parts 53 and 54 of the magnetizing element coils of the first conjunctive magnetizing coil series 51.

Thus, conjunctive magnetizing composite coils are formed having chain-like intersections at the top and the bottom parts. Superposition can be made in any such forms as simply laying these conjunctive magnetizing coil series one over the other or inserting one into the other so long as it is within the purpose of the present invention. Also, according to the present invention, the number of magnetizing element coils may be adjusted in accordance with the width of the test materials. The intersection 56 of the second conjunctive magnetizing coil series needs not be strictly the center of the opening 55 between the intersection 57 of the first conjunctive magnetizing coil series, but may be in the vicinity of the center. The magnetizing coils are serially coupled at their top and bottom portions, respectively.

At the center, that is, the boundary of the intersections 57 of the adjoining conjunctive magnetizing coil series, the magnetic fields produced at the intersection 56 interfere with each other to cancel the magnetic field in the direction of connecting magnetizing element coils, that is, in the width direction B, leaving a weakened field in the direction of travel A.

Therefore, it is impossible to have flaw detecting on an omnidirectional basis carried out at a position far away from the above-mentioned boundary part, that is, the intersections of magnetizing element coils. In order to solve this problem, the first and the second conjunctive magnetizing coil series are superposed, as mentioned above, and the current supply is switched alternately between these series, thus preventing simultaneous supply. Numerals 61, 62, 63, 64, and 65 and 66 indicate terminals of respective conjunctive magnetizing coil series for the connection with their electric power source. Each of these numerals is used for two terminals in order to point out the connection positions to the current source output terminals shown in FIG. 13.

The magnetic particle flaw detecting apparatus of the present invention, which is constructed as mentioned above, is operated in the following manner. A plate-like magnetic article, such as thick steel plate, is charged into the space formed by the conjunctive magnetic coil series 51 and 52 along the direction line A, and when it is in the air-core of the conjunctive magnetic composite coil for flaw detection, if it is so devised as to have the magnetic field produced on the surface of the test material form a circular rotating magnetic field, an omnidirectional magnetic field will periodically travel over the full width of the test material, making it possible to conduct flaw detection with the same level of detecting sensitivity on an omnidirectional basis.

In flaw detection of plate-like magnetic articles by using the apparatus of the present invention, a stronger magnetic field is produced in the direction of travel A of test materials, as such materials have already been magnetized from outside. However, the strengthening

action of the magnetic field is still small compared with the situation when testing long articles. Therefore, it becomes possible to make the magnetic field produced on the surface of the test material a substantially rotating magnetic field at the time the material is inserted into the coils by adjusting the ratio between the major axis (width direction) and the minor axis (direction of travel) of an elliptical rotating magnetic field to be between 1 and 2 at the time the conjunctive composite core is empty. In order to determine an appropriate value in the range between 1 and 2, such various factors as current phase difference and the crossing angle of crossed coils are considered; the most useful phase difference being 120°.

In this case, the crossing angle θ of magnetizing element coils is preferably between 120° and 90°.

FIG. 13 shows a circuit for connecting flaw detection coils 51 and 52 of the apparatus of the present invention to the current source.

In the figure, numerals 67, 68 and 69 indicate periodical current switches, such as 32 in FIG. 10. In the up position of the switches, only conjunctive series 51 is energized. In the down position, only conjunctive series 52 is energized. Numerals 70 and 71 denote respective transformers having V-connection with the three-phase current source. Letters U, V, W, u, v and w denote, respectively: the primary and the secondary phases of the terminals of the transformer. Letters R, S and T denote the phases of lines of the three-phase current source.

The inventors of the present invention were successful in omnidirectional flaw detection over the entire surface of thick steel plate test materials by using the magnetic particle flaw detecting apparatus constructed with the connection of magnetizing element coils intersecting at right angles, as shown in FIG. 12, and by using a three-phase alternating current having a phase difference of 120°.

This being the achievement of the apparatus of the present invention, it is now possible to subject broad plate-shaped magnetic articles to flaw detection on an omnidirectional basis over the whole surface area without contacting materials at high accuracy and efficiency.

What is claimed is:

1. An omnidirectional magnetic particle flaw detecting apparatus, comprising a first set of magnetizing coils consisting of a first planar composite coil and a second planar composite coil the planes positioned to intersect each other, each said composite coil being composed of two coils sharing one coil reel but having different numbers of coil turns, the coil turn ratio between the two coils of each coil composite being so determined as to produce a nearly circular rotating magnetic field on the surface of a test material when the test material is inserted into the magnetizing coils, and an alternating current source means coupled to the two coils of each said composite coils and supplying alternating current respectively differing in phase relative to the two coils, whereby surface flaws can be detected with the same sensitivity independent of the flaw direction.

2. The apparatus claimed in claim 1, wherein the angle formed by the intersection of the planes of the first composite coil and the second composite coil in the direction in which the test material is inserted is acute.

3. The apparatus claimed in claim 1, wherein the alternating currents supplied to said composite coils have a phase difference of 120°, and said coil turn ratio is between 1.5 and 2.5.

4. The apparatus claimed in claim 3, wherein the angle formed by the intersection of the planes of the first composite coil and the second composite coil is between 30° and 60°.

5. The device of claim 1, further comprising a second set of magnetizing coils consisting of a third planar composite coil and a fourth planar composite coil, the planes of said third and fourth composite coils being positioned to intersect each other and being positioned concentrically with said first and second composite coils such that an imaginary line connecting points of intersection of said first and second composite coils and an imaginary line connecting points of intersection of said third and fourth composite coil are at right angles and intersect at their respective centers, said third and fourth composite coils each consisting of two coils sharing one coil reel but having different numbers of

coil turns, the coil turn ratio therebetween being such as to form a nearly circular rotating magnetic field on the surface part of test materials when the test material is inserted into the magnetizing coils, and said third and fourth composite coils being coupled to said alternating current source means.

6. The apparatus of claim 5 wherein the angles respectively formed by the intersection of the planes of the first and second composite coils and the third and fourth composite coils in the direction in which the test material is inserted are acute.

7. The apparatus claimed in claim 5, wherein alternating current supplied respectively to said coils has a phase difference of 120°; and the said coil turn ratio is in the range between 1.5 and 2.5.

8. The apparatus claimed in claim 5, wherein the angle formed by the intersection respectively of the planes of the first composite coil and the second composite coil and the third and fourth composite coils are between 30° and 60°.
